GOLF BALL MARKING MACHINE

Eugene J. Russell, Yorba Linda, and Arthur E. Wilde, Long Beach, Calif.

Application November 10, 1947, Serial No. 784,948

2 Claims. (Cl. 101—4)

1

This invention is a token controlled machine for the ready, manual lettering of golf or other adaptable balls.

Cumbersome and expensive machines have been proposed for the marking of symbols or of letters, or numbers on game balls, especially golf-balls.

It is one objective of this invention to provide a simple, practical, substantial, low-cost and easily operative machine in which may be deposited a ball to be marked by a suitable or desired symbol or the lettered name of the owner of a given ball.

A further purpose of the invention is to provide a public service, ball marking device incorporating certain mechanism which can only be manipulated in the presence of a given token as a power transmitting agent whereby a control lock is releasable to permit use of the machine.

An additional object of the invention is to provide a token controlled, clamping means to hold a deposited ball, and a manually operative symbol or letter impression means whereby to firmly impress a letter die into the face of the inserted ball to be marked, and to provide for the orientation of the impression means around the equator of the ball to effect the impression therein of a long word or a full name or part thereof as desired.

The invention resides in the certain advancements in the art of marking balls as set forth in the ensuing disclosure and having, with the above, additional objects and advantages as will hereinafter develop, and whose construction, combinations and details of means, and the manner of operation thereof will be made manifest in the following description of the herewith illustrative embodiment; it being understood that modifications, variations and adaptations may be resorted to within the scope, spirit and principles of the invention as it is claimed in conclusion hereof.

Figure 1 is a top plan, and Figure 2 is a front elevation of the machine, both in idle or normal position of the parts. Figure 3 is a vertical, central, transverse section of the machine showing a ball set in the ball clamping device. Figure 4 is a plan, in partial section, of the coin or token controlled means relative to the ball clamp.

As shown, the machine has a substantial frame which embodies a bracket 2 for convenient fixation to a stand, a counter, or a wall, as the case may be, for the installation of the machine in public places for ready use by a patron wishing to mark a golf or other ball for which the ma-

2

chine may be adapted (in this instance for marking golf-balls).

On the bottom 3 of the bracket is swivelled, on a bushing 4, a vertical axis trunnion 5 having a transverse-axis shaft 6.

A ball marking means is movably mounted, as to the bracket, to carry a marking device up to a positioned ball B in a holder, later described. This marking means embodies a substantial, bifurcated arm 7 mounted on said shaft 6 which serves as an axis on which the said arm is manually raised and lowered in its functions.

The trunnion 5 has in its top face suitable row of indentations 5x into each of which is engageable a snap latch 8 whereby to yieldably hold the trunnion at any selected angular position about the trunnion axis while a clamped ball is being marked, around its belt, by a selected die symbol as later disclosed. The arm 7 normally stands outwardly inclined as to the vertical axis of the trunnion and from a money box 10 disposed above the trunnion, for compact arrangement. The upper end of the arm 7 has a cage 11 in which is mounted an upright spindle 12 on which is rigid a rotary, manual dial 13 having on its top face a marginal arc of index symbols S, such as a chosen language alphabet, each being presentable, by dial rotation, below a frontal, peep-hole 14 in a ledge of the rigid cage 11.

As the spindle 12 is rotated by the dial an impression, symbol die wheel 15 is rotated by its affixed spindle 12 to present a chosen, symbol die D at a rear window 11w, of the cage, for direct, manual thrust toward and against a ball B to be marked; in this case by an impression of a presented die D.

A simple, practical means is here incorporated whereby to hold the ball firmly while the operator manipulates the die carrier 7. The ball, in this holding device, is deposited in a position on the projected axis line of the trunnion 5 so that as the power arm 7 is swivelled thereabout the symbol dies will be engaged, as selected, on an equatorial zone horizontally around the ball, one symbol after the other for the stamping of a name around and on the said zone, as the desired symbol dies are dialed into functional, stamping position opposite the applied ball.

The holding device includes a hemispherical socket 16 which is rigid with the top of the box 10 and in such a position as to enable the dies D to impinge the horizontal belt of the ball, as stated above.

Control means are provided whereby to preclude the use of the machine until a proper

coin or token X has first been inserted in the control means and the latter is actuated by medium of the token as a transmission element to unlock the machine for use. A preferred locking and control means includes a hand lever 20 pivoted on a stud 21 in the frame and having a rearwardly extending and concealed crank limb 22 normally pressed upwardly by a substantial resistance spring 23 in the coin box.

The lever 20 has a cap-like clamp 24 which, when in idle, normal position, overhangs the socket 16 in such a degree of contiguity as to prevent a ball (for which the machine is adapted) from being deposited in the socket. This barrier position of the lever is determined by a control bolt 25, in the box 10, which is normally thrust by a spring 26 against the lever limb 22 or into a keeper-hole 22h therein and into which hole the bolt snaps as the keeper-hole registers therewith.

The control lever cannot be lifted to permit a ball to be deposited in the socket 16 until the bolt 25 is disengaged from the crank limb 22. Such disengagement is effected when a proper token X is placed in a pocket 27p of a manual, forwardly pulled, coin slide 27, extending into the coin box, and said loaded slide is forced inward. As the slide moves inward the interposed coin (or token) is rammed against a coin actuated sleeper 28 along which the slide forks. The sleeper is thus repressed by the coin and at the same time the bolt 25, which is riveted at 29 to, and is above, the sleeper, is repressed enough to be extracted from the keeper-hole 22h of the crank limb 22. When the control coin is later released of pressure of the manual slide 27 it falls into the money box.

The cap lever 20, when freed from the locking bolt, can be manually repressed far enough to permit a ball to be placed in the horizontal socket 16 under the momentarily raised cap lamp. The lever is then tipped forward by the crank spring 23 to snugly grip the cap onto the positioned ball.

Immediately following the clamping of the ball in and by the machine, the operator, or a patron, proceeds to set the die wheel for the first symbol impression on the gripped ball and so swings the carrier arm 7 as to place the first and chosen die D at a point of beginning the successive letter stamp of a name, for instance, on the equator of the fixed ball.

As each requisite letter die is so equatorially presented it is firmly impressed into the ball by manual pressure on the cage arm 7.

Finally the fully inscribed ball is drawn from the socket while the cap lever is still unlocked and while the cap is pressed up by hand high enough to clear the marked ball. When the lever

5

next again moves to a position with its keeper-hole in front of the spring bolt this snaps in and locks the lever, and this can be released only by medium of another proper token carried in by the slide 27.

Stop means, as lugs 30, limit the in and out strokes of the manual slide 27.

What is claimed is:

1. A ball marking machine having, in combination, a frame having a rigidly fixed ball support including an upwardly facing socket for nesting an applied ball in stable position, a ball clamping means including a lever having a horizontal axis on said frame and being radial from one side of the socket and having a downwardly facing cap movable by said lever toward and from the socket, a spring on the frame constantly urging the cap toward the socket to grip an applied ball, the lever being manually operative to move the cap away from the socket for insertion of a ball, a marking die member, and a carrier, on which the die member is mounted, pivoted on the frame for both a horizontal sweep around the socket and for vertical swing toward or from the socket whereby to press a die character against a contiguous surface of the clamped ball.

2. The machine of claim 1, said lever having a keeper-hole, a self-locking bolt mounted on said frame and normally latching in said hole, and a manually operative controller slidably mounted on the frame for disengaging the bolt from the lever to permit manual, cap-opening movement thereof.

EUGENE J. RUSSELL,
ARTHUR E. WILDE.
